UNITED STATES PATENT OFFICE.

WILHELM FRITSCH, OF MARIENBAD, AND ADALBERT SPRINGER, OF PILSEN,
AUSTRIA-HUNGARY.

COMBINED FIRING AND FUSE-REGULATING MECHANISM.

No. 922,877.

Specification of Letters Patent. Patented May 25, 1909.

Application filed September 25, 1908. Serial No. 454,812.

To all whom it may concern:

Be it known that we, WILHELM FRITSCH, a subject of the Emperor of Austria, and ADALBERT SPRINGER, a subject of the Emperor of Austria, residing the first at Marienbad, Austria, the second at Pilsen, Austria, have invented new and useful Improvements in Combined Firing and Fuse-Regulating Mechanism, of which the following is a specification.

This invention relates to a distance regulator for cannon, guns, etc. by means of which a number of discharges can be fired to the same distance by a single setting of the regulator scale. Heretofore the regulator had to be adjusted after each single shot or discharge but the present invention overcomes this defect while at the same time allowing a rapid loading and discharging of the fire-arm.

The adjustment of the regulator consists in setting a scale which in turn regulates the moment of release for the percussion bolt causing the discharge of the explosive which propels the projectile or cannon ball.

This invention is set forth in the following specification and claims and illustrated in the annexed drawing, in which:

Figure 1 is a side view of a breech portion 30 of a cannon embodying this invention. Fig. 2 is a sectional side view of a cannon embodying this invention and showing the parts in a position of rest. Fig. 3 is a like view showing the parts in a position of tension. Fig. 4 is a view similar to Fig. 2 showing the parts at the moment of firing. Fig. 5 is a section along line A—B Fig. 1. Fig. 6 is a section along line C—D Fig. 5. Figs. 7 to 12 are detail views of parts of the 40 firing and distance regulating mechanism on an enlarged scale.

In the above drawing the numeral 1 (Fig. 2) indicates a closing piece or breech block and 2 indicates a percussion bolt with 45 polygonal cross section (Figs. 2, 7 and 8.) Inside said percussion bolt 2 is located an actuating spring 3 and an abutment spring 4. The percussion bolt 2 as well as the tension piece 6 are slotted, through which slots 50 a bar 5 extends. This bar 5 is fixedly secured in the closing piece 1. The springs 3 and 4 bear against the bar 5. The percussion bolt 2 fits into the tension piece 6 or in other words the shell-like tension piece 6 is

slipped or slid over the percussion bolt. The 55 tension piece 6 carries an arm with pin 7 engaged by the inner end of the bell-crank shaped retracting lever 9 (Figs. 5 and 6) whose fulcrum 8 is mounted in closing piece 1. The retracting lever is held in a position 60 of rest by means of spring 10 (Fig. 6).

The tension piece 6 carries a trigger 11 which under the action of a spring is pressed into engagement with lug 12 on percussion bolt 2 thus causing the said percussion bolt 65 2 to move with the tension piece and compress the actuating spring 3.

A shell 13 (Fig. 10) is slid onto the forward end of the percussion bolt. Plate or cap 14 is secured in the forward end of the 70 percussion bolt and this cap will cause the shell 13 to move backward when the tension piece is retracted. The shell 13 has diametrically opposed pins 15 which fit into the screw-shaped grooves 16, 16 in shell 17 75 (Figs. 11 and 11^a). This shell 17 is secured against longitudinal movement but can rotate. Now when the tension piece 6 and percussion bolt 2 with shell 13 and plate or cap 14 is retracted by bell crank lever 9 the 80 pins 15 moving in the grooves 16, will cause the shell 17 to describe a nearly complete rotation in one direction while the return rotary motion will be effected when the tension piece 6 returns to its position of rest. The 85 shell 17 has on its front lugs or projections 18 (Figs. 1, 11 and 11^a) which when the closing piece is set home engage in groove 19 (Fig. 12). This groove 19 is formed in rod 21 rotatable in the bottom of the cartridge shell 20 and which rod is adapted to receive a percussion cap 22.

The front end of the rod 21 imparts the rotary movement of the shell 17 to the positioning disk of a double igniter 23 (Fig. 9 1) arranged in the bottom of the projectile. This double igniter can be of any suitable construction. The projectiles heretofore in use which had the igniter at their tip or forward end are thus done away with and the present construction presents the great advantage of use of integral projectiles having hardened tips. These latter projectiles can be used as shrapnell and as grenades against targets which offer resistance.

In order to regulate the flight of the projectile within the maximum distance of shot to any desired point there is provided an ad-

justable releasing nose 24 (Figs. 2 and 7) to release the trigger 11 from the lug 12 on the percussion cap or bolt 2.

When the tension piece 6 with shell 13 and percussion bolt 2 is moved by means of retracting lever 9 the free arm of the trigger 11 comes into contact with releasing lug 24 whereby the said trigger will be disengaged from the lug 12 on the percussion bolt. (Fig. 10 3) whereupon the percussion bolt thus released is forced into firing position (Fig. 4) under the influence of actuation spring 3. Now if the retracting lever 9 is released or let go the tension piece with shell 13 immediately 15 parts simultaneous return rotary motion to shell 17 and returns to a position of rest (Fig. 2).

In Figs. 2 and 7 the releasing lug 24 is shown in its extreme rear position in which 20 position the shell 17 describes an almost complete rotation before the trigger 11 disengages lug 12. In this position the projectile is fired to its greatest distance.

If it is now desired to fire the projectile 25 to a less distant point the distance between the releasing lug 24 and trigger 11 is decreased which will cause the percussion bolt 2 to come to its firing position earlier and also regulate the rotary motion of shell 17 30 and thus cause the projectile to be fired or discharged to a less distant point than heretofore.

If adjustment for smaller trajectory is required the shell 13 remains stationary at 35 the moment of firing and the tension piece 6 continues its rearward or backward motion under the influence of retracting lever 9, the movement of which is always uniform.

The releasing lug 24 is carried by a moving 40 rack which is in engagement with gear 25 (Figs. 2 to 5) mounted on spindle 27. To the spindle 27 is applied the spring or blade brake 26 and such spindle 27 also carries a hand wheel 28 provided with a scale 45 (Fig. 1). To the breech or closing portion is secured a stationary indicator 29 by means of which the distance to which the projectile is to be fired can be noted.

When the scale is turned in the direction 50 of the arrow (Fig. 1) until the indicator 29 registers with the last mark or graduation on such scale the releasing lug or nose 24 will be set to its extreme left or rear position (Figs. 2-4) in which case the time- 55 igniter is set out of action and at the moment of firing the percussion igniter of the projectile or grenade comes into action. The scale instead of being secured to the hand wheel 28 could be arranged directly on 60 the closing piece and a finger or indicator secured to the spindle 27 could serve for the adjustment of the releasing nose 24.

The correct position of the cartridge or projectile in the loading space of the cannon 65 is determined by a pointed thickening 30

(Figs. 1 to 3) engaging a similarly formed shoulder or depression in the wall of the bore or the loading space.

Now what we claim is:

1. A device of the character described 70 comprising a closing piece, a tension piece inside said closing piece, an arm with pin on the tension piece, a retracting bell crank lever engaging said pin, a percussion bolt, slots in the tension piece and percussion bolt, 75 a retracting spring and an abutment spring in said percussion bolt, a bar secured in the closing piece extending through the slots in the tension piece and percussion bolt for bracing the springs in said percussion bolt, 80 and means for releasing the percussion bolt to come into firing position.

2. A device of the character described 85 comprising a closing piece, a tension piece inside the closing piece, an arm on the tension piece, a pin carried by the arm, a retracting lever engaging said pin, a percussion bolt, actuating and abutment springs in 90 said percussion bolt, a bar bracing said springs, and means for releasing the percussion bolt to come into firing position, said means comprising a lug on the percussion bolt, a spring controlled trigger mounted on the tension piece and made to engage said lug, a movable toothed bar, a releasing lug 95 on said bar adapted to raise the trigger to release the percussion bolt and means for setting the said bar with releasing lug.

3. A device of the character described 100 comprising a closing piece, a tension piece inside the closing piece, a pin on the tension piece, a retracting lever engaging the pin, a percussion bolt in the tension piece, springs in the percussion bolt, slots in the tension piece and percussion bolt, a spring bracing 105 bar extending through the said slots, a spring pressed trigger for locking the percussion bolt to the tension piece, means for releasing said trigger, a shell on the forward end of the percussion bolt, a cap 110 on the percussion bolt to hold said shell in place, diametrically opposite pins on said shell, a second shell fitting over the first named shell and partly over the tension piece, and grooves in said second shell for 115 receiving the pins on the first named shell to rotate the second shell when the first named shell is moved.

4. A device of the character described 120 comprising a closing piece, a tension piece, a pin on the tension piece, a bell crank lever engaging said pin, a percussion bolt, springs in said percussion bolt, a bar bracing the said springs, a trigger for locking the percussion bolt to the tension piece, means for releasing said trigger to bring the percussion bolt to firing position, a shell on the percussion bolt, pins on said shell, a second shell fitting over the first named shell and partly over the tension piece, grooves in said 130

second shell adapted to be engaged by the pins on the first named shell to rotate the second shell when the percussion bolt and tension piece are moved, projections on the 5 front of the second shell, a cartridge shell having a rotary shaft provided with grooves for receiving the projections on the front of the second shell to impart the rotary motion of said second shell to the time igniter in 10 the cartridge.

5. A device of the character described comprising a closing piece, a tension piece, a pin on the tension piece, a bell crank lever engaging said pin, a percussion bolt, springs 15 in the percussion bolt, a bar bracing said springs, a trigger for locking the percussion bolt to the tension piece, means for releasing said trigger to bring the percussion bolt to firing position, a reciprocating shell on the percussion bolt, pins on said shell, a rotary shell fitting over said reciprocating shell, grooves in said rotary shell adapted to

receive the pins on the reciprocating shell to rotate the rotary shell when the tension piece and percussion bolt are moved and a cartridge having a rotary shaft, said rotary shaft in the cartridge and rotary shell being in engagement with one another to rotate the time igniter of the cartridge. 25

6. A device of the character described comprising a percussion bolt, an adjusting device automatically actuated by the retraction of the percussion bolt and an igniter in the projectile, said adjusting device being made to control the position of the igniter 30 according to the required trajectory. 35

In testimony whereof we have hereunto set our hands in the presence of two subscribing witnesses.
